THOMAS J. URELL, OF PITTSFIELD, MASSACHUSETTS.

SLIDE FOR MOTION-PICTURE MACHINES.

1,016,575.

Specification of Letters Patent.

Patented Feb. 6, 1912.

Application filed September 12, 1911. Serial No. 648,862.

To all whom it may concern:

Be it known that I, HANS A. MEINHARDT, a citizen of Germany, residing at Pittsfield, county of Berkshire, and State of Massachusetts, have invented a new and Improved Slide for Motion-Picture Machines, of which the following is a specification.

This invention relates to a slide of novel construction adapted to be exposed in a moving picture machine between the withdrawal of one film and the introduction of the next film. The slide is adapted to attract the attention of the audience while thus waiting, so as to while away the time and to simultaneously impart instructive information.

In the accompanying drawing: Figure 1 is a front elevation of a slide embodying my invention; Fig. 2 a horizontal section on line 2—2, Fig. 1; Fig. 3 a vertical section on line 3—3, Fig. 1, and Fig. 4 a front view of the rotatable disk detached.

The slide comprises essentially a plate 10 made of glass, mica or other transparent material and provided with a surrounding frame 11. Upon plate 10 there is represented preferably near one of the edges thereof, the dial 12 of a clock, such dial being thus integral with the plate and being likewise transparent. Through the center of dial 12, there passes an arbor 13 carrying at its forward end, *i. e.* in front of plate 10, an hour hand 14. Back of plate 10, there is mounted on the arbor, a rotatable transparent disk 15 upon which is represented by painting or otherwise an opaque minute hand 16, which is thus integral with the disk. The edge of disk 15 is preferably milled or corrugated as shown and this milled edge is partly exposed and rendered accessible by means of a finger notch 17 formed in plate 10 opposite the disk. In order to permit the finger to be readily introduced into this notch for engagement with the disk, frame 11 is cut away above the notch as shown. In addition to dial 12 here is represented upon plate 10, an advertisement, announcement or similar display matter 18 which is to be brought to the attention of the audience.

In use the hour hand 14 is set to the proper time by passing the operator's finger over the front of plate 10. The minute hand 16 is then set by rotating disk 15 by a finger introduced from the back of the plate 55 through notch 17, this operation being thus readily performed without liability of interfering with hand 14. After the hands have been set in the manner desired, the slide is introduced into the machine directly after 60 the withdrawal of one film and prior to the introduction of the next film. In this way the attention of the audience is held in an agreeable manner and the intermission is utilized for instructive purposes. 65

I claim:

1. A slide for moving picture machines, comprising a transparent plate, a clock dial represented thereon, an arbor carried by the plate and centered within the dial, an hour 70 hand mounted on the arbor in front of the plate, a transparent rotatable disk carried by the arbor back of the plate, and an opaque minute hand represented on the disk.

2. A slide for moving picture machines, 75 comprising a transparent plate having a finger notch and a dial represented on the plate in proximity to said notch, an arbor carried by the plate and centered within the dial, a transparent rotatable disk carried by 80 the arbor back of the plate, said disk being partly exposed through said notch, and an opaque hand represented on the disk.

3. A slide for moving picture machines comprising a transparent plate having a finger notch, a dial and display matter represented on the plate, an arbor carried by the plate and centered within the dial, an hour 85 hand mounted on the arbor in front of the plate, a transparent rotatable disk carried 90 by the arbor back of the plate, said disk being partly exposed through said notch, and an opaque minute hand represented on the disk.

4. A slide for moving picture machines, 95 comprising a transparent plate having a dial represented thereon, a transparent disk rotatably secured to the plate and having a first hand represented thereon, said disk projecting beyond the plate-edge so as to be 100

manually accessible, and a manually accessible second hand rotatably secured to the plate.

5. A slide for moving picture machines, comprising a transparent plate having a dial represented thereon, a transparent disk rotatably secured to one side of the plate and having a minute hand represented

thereon, said disk projecting beyond the plate edge so as to be manually accessible, ¹⁰ and a manually accessible hour hand pivoted to the other side of the slide.

HANS A. MEINHARDT.
